CLAIM

The ornamental design of a wireless network extender, as shown and described.

DESCRIPTION

FIG. 1 is a front view of a wireless network extender in accordance with the present invention;

FIG. 2 is a rear view of the wireless network extender of FIG. 1;

FIG. 3 is a right side view of the wireless network extender of FIG. 1;

FIG. 4 is a left side view of the wireless network extender of FIG. 1;

FIG. 5 is a top view of the wireless network extender of FIG. 1;

FIG. 6 is a bottom view of the wireless network extender of FIG. 1;

FIG. 7 is a first perspective view of the wireless network extender of FIG. 1;

FIG. 8 is an alternative perspective view of the wireless network extender of FIG. 7, shown in an alternate position for use;

FIG. 9 is an alternative front view of the wireless network extender of FIG. 1 shown plugged into an electrical outlet;

FIG. 10 is a front view of a second embodiment of a wireless network extender in accordance with the present invention;

FIG. 11 is a rear view of the wireless network extender of FIG. 10;

FIG. 12 is a right side view of the wireless network extender of FIG. 10;

FIG. 13 is a left side view of the wireless network extender of FIG. 10;

FIG. 14 is a top view of the wireless network extender of FIG. 10;

FIG. 15 is a bottom view of the wireless network extender of FIG. 10;

FIG. 16 is a first perspective view of the wireless network extender of FIG. 10;

(Continued)

FIG. 17 is an alternative perspective view of the wireless network extender of FIG. 16, shown in an alternate position for use; and,

FIG. 18 is an alternative front view of the wireless network extender of FIG. 10 shown plugged into an electrical outlet. The broken lines in FIGS. 9 and 18 showing the electrical outlet depict environmental subject matter, are for illustrative purposes only, and form no part of the claim.
